UNITED STATES PATENT OFFICE

125,134

DESIGN FOR A BOTTLE

Moritz M. Gottlieb, Allentown, Pa., assignor to Ben-Burk, Inc., Boston, Mass.

Application Aug. 17, 1940, Serial No. 94,473

Term of patent 14 years

To all whom it may concern:

Be it known that I, Moritz M. Gottlieb, a citizen of the United States, residing at Allentown, in the county of Lehigh, State of Pennsylvania, have invented a new, original, and ornamental Design for a Bottle, of which the following is a specification, reference being had to the accompanying drawing, forming a part thereof.

I claim:

The ornamental design for a bottle, substantially as shown.

MORITZ M. GOTTLIEB.
